UNITED STATES PATENT OFFICE.

GARRISON BABCOCK, OF EVERETT, WASHINGTON, ASSIGNOR TO AMERICAN TELECHRONOMETER COMPANY, OF EVERETT, WASHINGTON, A CORPORATION OF WASHINGTON.

TELEPHONE SYSTEM.

Application filed January 8, 1921. Serial No. 435,739.

To all whom it may concern:

Be it known that I, GARRISON BABCOCK, a citizen of the United States, residing at Everett, in the county of Snohomish and 5 State of Washington, have invented a certain new and useful Improvement in Telephone Systems, of which the following is a full, clear, concise, and exact description, reference being had to the accompanying 10 drawings, forming a part of this specification.

My invention relates to telephone systems, and more particularly to systems involving the use of a call meter or register.

Measured service as represented by the nickel in the slot machine had always been unsatisfactory and is at present particularly so in view of the increases in rates which have been placed upon telephone service which require a payment of more than five cents per message. Obviously, if the charge for service were based upon the number of calls and the duration thereof, a fair charge could always be made. My present 20 invention provides a system of very flexible character which involves no impediments to perfect service, and which can be employed upon either manual or machine switching systems. The invention is also applicable 25 to party line systems, and means is provided to prevent the registration of a call on the instrument of a party coming in on a busy party line, or where the subscriber has an individual line and calls a busy line, or calls 30 a line which does not answer. This particular means is disclosed and claimed in my prior Patent, No. 1,138,175, granted May 4, 1915.

This means which comprises a shunt 40 across the transmitter and the setting coil of the meter permits the subscriber to listen, but deprives him of the use of the transmitter until the safety button is released whereupon the message meter is made operative.

Fundamentally, the central station apparatus employs means for reversing the polarity of current supplied to the calling subscriber's line after the called party responds. 50 This function is produced by the incorporation of a pole changing relay in each answering unit—in the answering cord of the manual system, or in the selector switch control feed of the machine switching system, and is controlled through the super-

vised relays or their equivalents which are under the control of the called line.

In a system of this character, the measurement of service to private branch exchanges or to automatic branch exchange 60 systems is readily accomplished by adapting an automatic message meter to each trunk line. Such meters are common to all operators of the private branch exchange or dials of the automatic branch exchange system. 65

The present invention is an improvement upon the systems shown in my prior patents, namely No. 1,138,174, No. 1,138,175, No. 1,186,464, No. 1,189,525, and No. 1,230,835. The present invention is particularly concerned with the registration of messages which are limited to three, or five, or some definite number of minutes in duration. For this purpose, a time control is added to the central office equipment, which functions 70 to open the circuit between subscribers and place a "tone" signal on the line of the calling party, which will notify the calling subscriber to lower the switch hook, for the purpose of registering the limited call and when this is done, the connection is automatically 75 re-established between the subscribers and another one or more messages will be recorded according to the length of the connection. This operation is repeated as many 80 times in a conversation as there are multiples of the time limit. The arrangement is particularly adapted to automatic and semi-automatic systems where there is no operator supervision. 85

In order to acquaint those skilled in the art with the manner of constructing and operating my invention, I shall now describe a specific embodiment of the same in connection with the accompanying drawing 95 which shows a diagrammatic arrangement employing the invention.

In the diagram shown, I have illustrated two party lines, one of which has connected thereto the subscriber's stations A and A' and the other of which has connected thereto the subscriber's stations B and B'. I have also indicated a connecting circuit in the form of a cord circuit C, which is adapted to be located at the central station to 100 make connection between these lines. The line of the parties A and A' comprises the line wires 1 and 2 and the line of the parties B and B' comprises the line wires 3—4. In connection with the following description, 110

we will assume that the party A called and is connected for conversation to the telephone set of the party B. The apparatus at the station A comprises the usual telephone set including the receiver 5, transmitter 6, call bell 7, and automatic hook switch 8. In addition, I provide the message meter 9 adapted to be operated in two stages through reversal of current upon the line. The apparatus at the station B is the same as that at the station A. At the central station, the cord circuit C is provided with the pole changing device 10 connected to the answering end of the circuit and the time controlled interrupting device 92 for compelling the registration of another count upon the meter of the calling party upon the completion of a predetermined time interval of connection between the calling and called parties.

I have shown a three-strand cord circuit for connecting the two lines, but it is to be understood that a two-strand cord circuit may be employed as is disclosed in my prior 25 patents, and it is to be further understood that where a machine switch is employed at central, the pole changer 10 with the interrupting device 92 is employed in connection with the selector.

30 The hook switch 8 comprises the usual switch lever 12 of any preferred construction having a hook at its outer end for receiving the receiver 5 and having the springs 13, 14, 15, 16 and 17 of which the two main 35 springs 13 and 16 are connected together and are permanently connected to the line wire 2 through the conductor 18. The contact spring 14 is connected through the primary winding of the induction coil 19 and by way 40 of conductor 20 through the transmitter 6 through the instrument wire 21. This instrument wire 21 is adapted to be connected through either the contacts 22-23 or the contacts 24-25 to the instrument wire 26 45 which in turn is connected to the line wire 1. A constant connection between the instrument wires 21 and 26 exists through the winding of the setting coil 27 of the meter 9. The contacts 22-23 and 24-25 are adapted 50 to shunt out the coil 27 after said coil has been energized, or upon the occurrence of polarity which should cause operation of the meter as distinguished from setting of the same.

55 The meter 9 comprises the setting coil 27 and the operating coil 28, both of which are arranged to act upon the polarized armature 31. This armature bears a pawl 32 for operating the counter 33, which is in the nature 60 of a Veeder counter.

The one terminal of the operating winding of the coil 28 is connected through the wire 30 through the instrument wire 26 and from there to the line wire 1, the other terminal of said coil being connected by wire

34 through the contact spring 35, which operates with a contact spring 36 to prepare a circuit for the coil 28 when the setting coil 27 is properly energized. The contact spring 36 is connected by way of the instrument wire 37 to the hook switch spring 17, contact being made between the springs 16 and 17 when the receiver 5 is replaced upon the hook.

75 The polarized ringer 7 is connected directly across the line wires 1 and 2 through the medium of the condenser 38 and instrument wire 39. The switch spring 15 is connected by way of an instrument wire 40 to shunt out the condenser 38 when the switch 80 hook is raised, so that the direct current which then tends to flow through the coils of the ringer will control the contact 22-23 to insure that resetting of the meter will not occur unless proper polarity of current 85 exists upon the line.

90 The subscriber's station is provided with a safety device of the character described and claimed in my prior Patent No. 1,138-175 for shunting out simultaneously the transmitter 6 and the resetting coil 27 so that a subscriber may listen in on a party line to find out whether the same is or is not in use, and also to permit the subscriber 95 to receive a reply from a called party and thus ascertain whether the correct number has made response before subjecting himself to a charge for a message. This device 100 comprises the button 41 and the springs 42 and 43, the button 41 comprising a slide which lies directly below the switch lever 12, so that the contacts 42 and 43 are automatically closed when the switch hook lever is depressed.

105 The subscriber's line 1-2 is provided with the answering jack in this case shown as consisting of the springs 45-46 and the ring contact 47, the ring contact in this case controlling the operation of the cut-off relay 48 for disconnecting the line signal relay 49 to efface the line signal 50 when the answering plug is inserted in the jack of the calling party.

110 The cord C comprises three strands, namely, the tip strand 54, the sleeve strand 55, and a ring strand 56 and similar strands 54', 55' and 56' at the ringing end of the cord circuit. The answering and ringing ends of the strands are separated by condensers 57 and 58 which, however, permit the transmission of speech therethrough.

115 The answering end of the cord circuit C is provided with a key 59 for connecting the operator's set 60-61 to the cord and is provided at the ringing end with a key 62 for applying ringing current from a ringing generator 63 to the coiled line.

120 The system is supplied with current from a common source of current supply which, in this case, is illustrated at the battery 51

to which are connected the battery busses 52 and 53. The answering end of the cord is provided with the tip and sleeve supervisory relays 64 and 65 respectively, the battery connections for these relays being cut through the pole changing switch 10. The pole changing switch 10 comprises the armature contacts 67, 68 and 69 which cooperate with the stationary contacts 70, 71, 72 and 73. Current is fed to the tip strand of the cord from the battery 51 over the battery wire 74, contacts 67, 71 over the wire 76 through the relay 64 and through the strand 54. In the same manner, negative battery is normally supplied to the sleeve strand over the battery wire 75, contacts 68-72, wire 77, relay 65 to the strand 55. The supervisory signal which is controlled by the supervisory relays 64 and 65 is not shown, as this is well understood and need not be illustrated.

The circuit of the pole changer relay 66 is controlled at the contacts 78 and 79 of the tip supervisory relay 64' at the ringing end 25 of the cord circuit. Battery is supplied through the tip relay 64' to the ringing end of the cord circuit over the battery wire 80. The polarity of the tip strand at both answering and ringing ends of the cord circuit 30 is the same until the pole changing relay 66 operates to reverse the polarity on the answering end of the cord circuit.

Current is supplied to the sleeve strand 55' of the ringing end of the cord circuit over battery wire 81 and supervisor relay 65'.

I have provided an interrupting relay 82 which has the armature contacts 83, 84 and 85. These armature contacts 84 and 85 cooperate with back contacts 86 and 87 to interrupt the continuity of the cord circuit whereby conversation between the connected parties is interrupted, and cooperate with the front contacts 88 and 89 to apply a tone 45 signal to the calling line to notify the calling subscriber to lower and again raise his switch hook, in order to continue the conversation between the connected parties.

The circuit of the pole changer relay 66 is 50 cut through the contacts 83 and 90 of the interrupting relay 82, so that when the interrupting relay 82 is operated to attract its armature contact, the circuit of the pole changing relay 66 will be opened and the armature contacts 67, 68 and 69 will be 55 shifted to restore normal polarity of current on the calling line for operating the operating coil of the meter at the calling subscriber's station. The circuit of the pole changing relay 66 may be traced over the battery wire 75 through the winding of the relay 66, contacts 83 and 90, wire 91, contacts 78 and 79 of the supervisory relay 64' and back to battery over the battery wire 80. The interrupting relay 82 is actuated

periodically, namely, at the end of a predetermined period of time after connection between the calling party and the called party is established. For this purpose, I provide the timing device which comprises 70 a timing wheel 92 having a raised cam portion 93 and a contact controlling finger 94 cooperating with the contacts 95 and 96. The wheel 92 is adapted to be driven by means of the friction wheel 97 and is 75 adapted to be returned to its normal position by the spring 98. The wheel 92 is held against movement by means of the detent 99 formed on the armature 100 of the starting relay 101. The starting relay 101 is controlled by the pole changer relay contacts 69 and 73 and since the pole changer relay 66 is under the control of the supervisor relay 64' at the ringing end of the cord circuit, it will be apparent that the starting relay 101 is operated to start the timing wheel 92 only when the called party 80 responds.

The timing wheel 92 is driven by the friction wheel 97 which friction wheel is driven 90 in turn by the constant speed motor 103, the circuit of which motor is closed by the timing relay contacts 100 and 102. The shaft of the motor 103 is provided with a flexible coupling 105 and has an armature 95 106 controlled by the magnet 107 for applying the driving wheel 97 to the timing wheel 92. This arrangement merely illustrates a form of electrically controlled clutch for connecting together the motor 103 or other suitable source of constant or substantially constant motion with the timing wheel 92. The magnet 107 is controlled 100 at the contacts 108 and 109 of the tip supervisor relay 64 on the calling subscriber's end of the cord circuit. The circuit for the magnet 107 may be traced over the battery wire 75, contacts 108-109, wire 110, winding 107 to battery wire 80.

If desired, the control of the magnets 101 and 107 may be interchanged since the operation of both of these is required to start the timing device.

The supervisory signal on the ringing end 111 of the cord circuit has not been shown, as this is well understood in the art.

I believe that the operation of the system will be fully apparent from the foregoing detailed description, but I shall recapitulate briefly the sequence of operations and 112 the relation of the same.

Assume that the calling party A has called central and desires to be connected to the called party B. When the switch hook is 12 down, the contacts 13-14 and 15-16 are opened, so that the talking circuit is interrupted. The contacts 16-17 are closed and the meter 9 is in the position shown in the drawing with the contacts 35-36 open and the contacts 24-25 open. The contacts 42 13

and 43 at the safety button 41 are closed since the slide of the button has been forced down by lowering of the hook switch lever 12. The calling party removes the receiver 5 from the switch hook opening the contacts 16 and 17 closing contacts 13—14 and 15—16. The polarity of current is now such that whatever flow of current there is to the ringer coils 7 tends to keep the contacts 22 10 and 23 closed. This protects the setting coil 27 from operation. At the same time, the contacts 42 and 43 are closed until the safety button is raised, which latter operation is necessary in order to render the transmitter 15 6 operative. As soon as the switch hook is raised, the line signal 50 at central will be energized and the operator inserts the answering end of the cord circuit into the contacts of the jack whereupon the cut-off relay 20 48 is energized and the subscriber's line is extended to the strands of the cord circuit. The operator then operates the button 59 to place her talking instruments 60 and 61 in connection with those of the subscriber A. 25 Battery is supplied to the line of the calling subscriber over the following circuits:

From common battery 51, battery wire 74, pole changer contacts 67 and 71, wire 76, tip supervisor relay 64, tip strand 54, 30 line wire 2 to the instrument wire 18, contacts 13 and 14 through the primary winding of the induction coil 19 through the instrument wire 20, transmitter 6, instrument wire 21, contacts 22, 23, instrument wire 35 26, line wire 1, sleeve strand 55, supervisor relay 65, pole changer contacts 72 and 68 back to battery over the battery wire 75.

The operator having ascertained the 40 number of the wanted subscriber inserts the ringing plug in the multiple jack of the called subscriber and projects ringing current over the called line through the ringer of the called party over the following circuit:

45 From the ringer 63, line wire 3, instrument wire 18, wire 39, condenser 38, ringer 7, instrument wire 26 and back over line wire 4 through the ringing generator 63.

If the calling party desires, he may 50 depress the slide 41 to shunt out the transmitter 6 and setting coil 27 of his meter to await the response of the called party. When the called party removes the receiver from the switch hook and responds to the 55 call, the calling party is apprised that the called party is the proper one, then raises the safety slide and button 41 to place his transmitter 6 in operative condition and to permit the setting coil 27 of the meter to be 60 operated to set the meter.

Battery is supplied through the line of the called party over the following circuit:

65 Battery 51, battery wire 80, tip relay 64', tip strand 54', line wire 3 through the instrument of the called party B as previous-

ly traced in connection with the calling party A back over the line wire 4, sleeve strand 55', sleeve relay 65' and back to battery over the battery wire 81.

The energization of the tip supervisor 70 relay 64' closes the contacts 78, 79 and energizes the pole changer relay 66 to reverse the polarity of current on the calling line. At the same time, the contacts 69 and 73 are closed, these contacts serving to energize the 75 starting relay 101 which lifts the nose 99 of the armature 100 from in front of the raised portion 93 and at the same time, closing the contacts 100 and 102 to energize the driving motor 103. The motor being energized begins to rotate the timing wheel 92 in the direction indicated by the arrow. It will be understood that the clutch magnet 107 was energized by the closing of contacts 108 and 109, these contacts being under the 80 control of the calling party's supervisor relay 64. The timing wheel 92 thereupon begins to operate, the raised portion of the cam 93 holding the contacts 100 and 102 closed until a predetermined time interval 85 has elapsed, this time interval being determined by the time required to rotate the finger 94 from the position shown in the drawings into a position where it closes the contacts 95 and 96. When these contacts 95 90 and 96 are closed, a circuit is closed for the interrupting relay 82 as follows:

Battery 51, battery wire 81, contacts 95 and 96, wire 112, interrupting relay 82 and 100 battery wire 74.

The energization of interrupting relay 82 opens the contacts 84, 86 and 85, 87 interrupting the conversation between the parties and applying a tone signal to the calling party's line to apprise him of the fact that the period of one call has elapsed. To restore the connection, it is now necessary for the calling party to lower the switch-hook and again raise the same and to open the contacts 42, 43 whereupon the conversation 110 between parties may be resumed. When the interrupting relay 82 is operated, the contacts 85 and 84 are applied to the contacts 89 and 88 respectively, which contacts connect to a suitable source of signaling current. Since clutch magnet 107 is still energized and friction wheel 97 still tends to drive the timing wheel 92, the contacts 95 and 96 will be compelled to close by the finger 94 until the clutch magnet 107 is de-energized. This is under the control of the 115 calling supervisory relay 64 and consequently, it will be necessary for the calling party to open the circuit in order to permit the return of the timing wheel 92 to its position as shown in the drawing, whereupon the contacts 95 and 96 will be again opened and the interrupting relay 82 de-energized. 120

I shall now explain more in detail the operation of the pole changer relay in connec- 125

tion with the meter, which occurs throughout these various stages which I have above outlined.

When the called party responds, pole changer relay 66 is energized, as I have previously indicated, to send reverse current out over the line of the calling party. Such reversal of current energizes the windings of the ringer bell 7 to open the contacts 22, 23 thereby removing the shunt on the magnet coil 27 which is thereupon energized to attract the adjacent portion of the armature 31 closing contacts 24, 25 to shunt out further passage of current through the coil 27 and to close the contacts 35 and 36 to prepare the operating coil 28 for operation of the counter 33. The conversation now proceeds to the time when the timing wheel 92 closes the contacts 95 and 96 whereupon the 20 interrupting relay 82 is energized, this interrupting relay opening the circuit for the pole changer relay 66 at the contacts 83 and 90 whereupon the pole changing relay 66 drops its armatures restoring normal current to the line. As the calling subscriber now depresses the switch hook for the purpose of restoring service, contact is closed between the springs 16 and 17 at the switch hook, and the operating coil 28 of the meter 30 is energized over the following circuit:

Battery 51, battery wire 74, pole changer contacts 67 and 71, wire 76, supervisor relay 64, tip strand 54, line wire 2, instrument wire 18, contact 16, contact 17, instrument wire 37, contacts 35 and 36, operating coil 28 of the meter, instrument wire 30, line wire 1, sleeve strand 55, relay 65, pole changer contact 72 and 68 back to battery over the battery wire 75. This causes the actuation of the meter and opens the contacts 35, 36 and 24, 25 so that when the called party raises the switch hook to resume the conversation, the setting coil 27 of the relay will again be energized as soon as the interrupting relay 82 is de-energized. The de-energization of this relay again closes the circuit for the pole changer relay 66 at the contacts 83 and 90, thereby again permitting reverse current to be sent out over the calling line to again set the meter for the next charge which will be made. This operation will be repeated for every multiple of the period of limited service through which the call extends. Upon the completion of the conversation, the parties restore the receivers to the switch hook, this act at the calling party's station causing the operating coil 28 to be energized again opening the circuit of the instrument and at the same time, adding another count to the message meter.

I do not intend to limit the invention to the precise details of construction shown and described.

I claim:

1. In a telephone system a calling line hav-

ing telephone instruments and having a message meter, a called line also having telephone instruments, means for switching said lines into talking connection, said means comprising mechanism dependent upon the response of the called party and being under the control of the calling line for operating said meter to register a count upon the expiration of each predetermined period or any multiple of the same and means for permitting the calling party to listen to the response of the called party at each registration before submitting to further registration.

2. In a telephone system a calling line having a telephone set and having a message meter operable by reverse current on the calling line, a called line also having a telephone set including a switch hook, means for switching said lines into talking connection, said means comprising a switch for setting said message meter upon a response of the called party, and means dependent upon the continuing response of the called party and under the control of the switch hook of the calling line for operating said meter to register a count upon the expiration of a predetermined period or any multiple of the same during the connection, and means under control of the calling party to permit the response of the called party to be heard by the calling party before registration is effected.

3. In combination, a calling telephone line having a meter requiring reverse current to set it and direct current to operate it, a plurality of called lines, a connection for supplying direct current to the calling line to permit the calling line to establish a connection, means under control of the calling party to prevent registration on the meter until the correct party responds, means for reversing current upon the calling line upon response of a connected called line to set the meter, a timing device, and means jointly controlled by the timing device and by the calling line for sending out direct current over the calling line to operate the meter.

4. In a telephone system a calling line having a telephone set and having a message meter, a called line also having a telephone set, means for switching said lines into talking connection, said means comprising mechanism dependent upon the response of the called party, and under the control of the calling line, for operating said meter to register a count upon the expiration of a predetermined period or any multiple of the same, and for operating the meter to register a count upon restoring the receiver to the switch-hook at the calling party's station and means for connecting the receiver only of the calling party to the called line before each registration.

5. In a telephone system a calling line having a telephone set and having a message

- meter operable by reversals of polarity on the line, a called line having a telephone set, a connecting circuit comprising a pole changer for changing the polarity of current upon the calling party's line when the called party responds, and means for interrupting said circuit and restoring the normal polarity upon the line at the end of the predetermined period or any multiple thereof, said means comprising a timer for disconnecting the parties and setting the meter and means controlled by the switch hook of the calling party for re-establishing the connection and actuating the meter to register or count.
6. In a telephone system a calling line having a telephone set and having a message meter operable by reversals of polarity on the line, a called line having a telephone set, a connecting circuit comprising a pole changer for changing the polarity of current upon the calling party's line when the called party responds, a timer at central station for periodically interrupting said circuit and restoring the normal polarity upon the line at the end of a predetermined period, and means under the control of the calling party for first listening on the line of the called party then restoring the connection and means under the control of the switch of the calling party for again placing reversed polarity of current upon the calling line.
7. In combination, a calling line having a telephone set, a called line having a telephone set, a meter at the telephone set of the calling subscriber, a connecting circuit for connecting the lines of the two sets into communication, said meter being operated by normal polarity of current on the calling line and being set for operation by reverse polarity of current on the calling line, a pole changer switch for supplying normal polarity of current until the called party responds and for then supplying reverse polarity upon the calling line, and timing means for interrupting the connecting circuit, said timing means governing the pole changer to supply normal polarity to the line for operating the meter and means for warning the calling party of the expiration of each period of time.
8. In combination, a calling line having a telephone set, a called line having a telephone set, a meter at the telephone set of the calling subscriber, a connecting circuit for connecting the lines of the two sets into communication, said meter being operated by normal polarity of current on the calling line, and being set for operation by reverse polarity of current on the calling line, a pole changer switch for supplying normal polarity of current until the called party responds and for then supplying reverse polarity upon the calling line, and timing means for interrupting the connecting circuit, said timing means governing the pole changer to supply normal polarity to the line for operating the meter and means for again setting the meter of the calling party.
9. In combination a calling line having a telephone set and a meter operated by normal polarity of current when the receiver is restored to the switch-hook and being set by reversal of polarity of current on the line when the receiver is off the switch-hook, a called line having a telephone set and a connecting circuit for connecting said lines in telephonic communication, a pole changer switch for supplying normal polarity to the calling line until the called party responds and for then supplying reverse polarity to the calling line whereby the meter is set, timing means for interrupting the connecting circuit, said timing means governing the pole changer to supply normal polarity to the calling line for operating the meter as soon as the receiver of the calling party is replaced on the switch-hook.
10. In combination a calling line having a telephone set and a meter operated by normal polarity of current when the receiver is restored to the switch-hook and being set by reversal of polarity of current on the line when the receiver is off the switch-hook, a called line having a telephone set and a connecting circuit for connecting said lines in telephonic communication, a pole changer switch for supplying normal polarity to the calling line until the called party responds and for then supplying reverse polarity to the calling line whereby the meter is set, timing means for interrupting the connecting circuit, said timing means governing the pole changer to supply normal polarity to the calling line for operating the meter as soon as the receiver of the calling party is replaced on the switch-hook, and means under the control of the switch-hook of the calling party for restoring the connection and operating the pole changer to supply reverse polarity for again setting the meter of the calling party.
11. In combination a calling line having a telephone set and having a message meter, a called line having a telephone set, means for inter-connecting said lines for telephonic communication, timing means for opening the connection at the end of a predetermined period and means for warning the calling party of the expiration of each period of time.
12. In combination a calling telephone line having a telephone set, a called line having a telephone set, a meter connected to the line of the calling party, switching

means for connecting said lines in telephonic communication, timing means for opening the connection between said lines at the end of the predetermined period, and 5 means under the control of the calling party's switch-hook for restoring the connection and for actuating the meter upon each opening of the connection by said timing means and means for warning the calling party of the expiration of each period of time.

13. In combination a calling line having a telephone set, a called line having a telephone set, a message meter connected to the 15 calling line, said message meter being controlled by reversals of polarity for operating the meter upon restoration of the receiver to the switch-hook at the calling party's telephone set, means for inter-connecting the lines for telephonic communication, timing means for interrupting said connection until the calling party restores his receiver to the switch-hook, and means for changing the polarity of current on the 20 calling line when the line is interrupted and for again changing the polarity when the connection is restored.

14. A connecting circuit for a telephone line comprising a timing device for opening 30 the connection between the answering end and the calling end of said circuit, said timing means being started upon response of the called party, and being restored upon interruption of the calling line by the calling party to its normal or starting position, and means controlled by the timing device after the timing device has completed a predetermined movement for reversing the polarity of current upon the answering end of 35 the connecting circuit, for operating the meter of a calling party.

15. In a connecting circuit for inter-connecting a calling line and a called line, an interrupting relay for opening the connection between the answering end and the calling end of the connecting circuit, a timing device controlling the operation of said relay, said timing device being started upon the flow of current out over the called line 50 to the telephone instrument of the called party, a pole changing switch for controlling the polarity of current supplied to the telephone instrument of the calling party, said pole changing switch being under the control of said interrupting relay whereby the pole changer relay will be operated upon making and breaking of the circuit at the interrupting relay, and means under the control of the calling line for re-starting 55 the timing device and for closing the connection between the answering end and the calling end of the connecting circuit.

16. In combination, a timing wheel, a 60 pair of contacts controlled by the timing wheel, a cord circuit having an interrupt-

ing relay controlled by said contacts, a pole changer relay for varying the polarity of current sent to the answering end of the cord circuit, a supervisory relay for the answering end of the cord circuit for controlling the restoration of the timing device to starting position, a supervisory relay for the ringing end of the cord circuit for operating the pole changer switch and for starting the timing device into operation, 75 said pole changer relay being under the control of the interrupting relay.

17. In combination a connecting circuit for interconnecting a calling and a called line, means for supplying current to the answering end of said connecting circuit, said means including a pole changer relay actuated upon response of the called party, an interrupting relay for interrupting connection of the connecting circuit and of the 80 pole changer relay, a timing device started by operation of the pole changer relay, said device being adapted to energize the interrupting relay upon the expiration of a predetermined period of time, and re-setting 85 means for the timing device controlled by opening of the circuit of the calling party's line.

18. In combination a calling party's line having a telephone instrument, a called 95 party's line having a telephone instrument, a message meter connected to the calling line, a connecting circuit for interconnecting the lines for telephonic communication, interrupting means for opening said connecting means, a timing means controlling said interrupting means, and means for projecting a distinctive signal over the calling line to advise the calling party that a predetermined period of time has elapsed during the 100 connection of the calling and called line.

19. In combination a calling line having a telephone set and having a message meter connected in circuit and adapted to be operated upon restoration of the receiver to the switch-hook, a called line having a telephone instrument, a connecting circuit for interconnecting the lines, an interrupting device for opening said connecting circuit without total loss of the connection between 110 the parties, timing means controlling said interrupting means, and means governed by restoration of the receiver to the switch-hook at the calling party's line for restoring the opened connection and for actuating the meter.

20. In combination a calling line, a called line, each of said lines having telephone instruments, and a meter at the calling party's station connected to the calling line, a connecting circuit, an interrupting device for opening the connecting circuit without total loss of the connection between the parties, said interrupting device being time-controlled, and means controlled by the sub- 125 130

scriber in registering a call for closing the open connection of said interrupting device.

21. In combination a calling line having telephone instruments and a switch-hook, a meter for said calling line controlled jointly by reversals of polarity on the line and by said switch-hook, a called line having a telephone instrument, a connecting circuit having means for supplying current to the calling line, a pole changer for the connecting circuit, and a timing device governing the operation of the pole changer and compelling the lowering of the switch-hook when the connection consumes more than a predetermined period.

22. In combination a calling line having telephone instruments and a switch-hook, a meter for the calling line, said meter being controlled jointly by reversals of polarity on the line and by said switch-hook, a called line having a telephone instrument, a con-

necting circuit having means for supplying current to the calling line, a pole changer for said connecting circuit under the control of the called party's switch-hook, an interrupting device for opening the connecting circuit, and a timing device also controlling said pole changer and governing the interrupting device.

23. In combination, a calling line having telephone instruments and a switch-hook, a meter for said line, controlled jointly by reversals of polarity on the line and by said switch-hook, means at the central station for reversing the polarity of current on the line, and for compelling the lowering of the switch-hook to continue the connection for more than a predetermined period.

In witness whereof, I hereunto subscribe my name this 29th day of December 1920.

GARRISON BABCOCK.
